Primary Examiner — Catherine A Tuttle(74) *Attorney, Agent, or Firm* — Calfee, Halter & Griswold, LLP**CLAIM**

I claim the ornamental design for a mat, as shown and described.

DESCRIPTION

FIG. 1 is a front/left/top perspective view of a mat;
 FIG. 2 is a rear/right/bottom perspective view thereof;
 FIG. 3 is a front elevational view thereof (the opposing rear view being a mirror image thereof);
 FIG. 4 is a right side elevational view thereof (a left side elevational view would be a mirror image thereof);
 FIG. 5 is a top plan view thereof; and,
 FIG. 6 is a bottom plan view thereof.
 The broken lines representing the trademark and the array of small surface projections form no part of the claimed design.
